UNITED STATES PATENT OFFICE.

JOHN HEBERLING, OF ROCHESTER, NEW YORK, ASSIGNOR TO HICKOK MANUFACTURING COMPANY, INC., OF ROCHESTER, NEW YORK, A CORPORATION OF NEW YORK.

BELT BUCKLE.

Application filed June 13, 1922. Serial No. 568,031.

To all whom it may concern:

Be it known that I, JOHN HEBERLING, a citizen of the United States, and resident of Rochester, in the county of Monroe and 5 State of New York, have invented certain new and useful Improvements in Belt Buckles, of which the following is a specification.

The present invention relates to buckles 10 and more particularly to the type in which a pivotally mounted anchoring means for one end of the belt is formed of relatively movable members to permit their separation, in order to connect such end of the belt 15 to the buckle frame. An object of this invention is to connect with said pivotally mounted anchoring means of the type mentioned a clamping means for the other end of the belt to cooperate with the clamping 20 surface on the buckle frame. A further object of the invention is to provide an anchoring means for one end of the belt embodying two members each having a belt engaging portion extending toward the belt 25 engaging portion of the other member, said members having relative movement to permit separation of the belt engaging portions and having clamping surfaces thereon for cooperating with the clamping surface on 30 the buckle frame for the securing of the other end of the belt.

To these and other ends, the invention consists of certain parts and combinations of parts, all of which will be hereinafter 35 described; the novel features being pointed out in the appended claims.

In the drawings:

Fig. 1 is a face view of a belt buckle constructed in accordance with this invention;

Fig. 2 is a section on the line 2—2, Fig. 1;

Fig. 3 is an enlarged rear view of the buckle; and

Fig. 4 is a section on the line 4—4, Fig. 2.

In the illustrated embodiment of the invention there is embodied a buckle frame comprising, in this instance, a front plate 1 formed from sheet metal and having side flanges 2 with inwardly turned portions 3 at their inner edges. One end 4 of the belt 50 has a loop preferably formed permanently by doubling the belt upon itself and securing the overlapping portions with stitches 5. This end of the belt is attached to the buckle by an anchoring means which, in this in-

stance, comprises two members 6, mounted 55 to turn about a common axis preferably by providing a pivot rod 7 connecting the side flanges 2 and providing said members with sleeves 6^a turning on said rod. Each member is further provided with a 60 portion 6^b extending toward the like portion on the other member. When these two portions are moved out of alignment, the loop 4 is adapted to be fitted over such portions and when tension is placed upon the 65 belt, these two portions swing into alignment and hold the belt end 4 against accidental disconnection from the anchoring means. While, in this instance, the two members of the belt anchoring means are shown 70 as relatively movable about a common axis, it is apparent, however, that the invention is not limited to this arrangement. In a patent granted to me on the 12th day of September 1922, No. 1,429,139, there is illustrated 75 a number of different anchoring means which could be employed in connection with this invention.

The invention also employs a clamping means for the other end of the belt to cooperate with a clamping surface on the buckle frame, in this instance, the front plate 2 to secure the other end of the belt, this clamping means being movable with the anchoring means about the pivot of the latter. In this instance, this clamping means embodies two clamping surfaces 8, each formed on one of the anchoring members 6 adjacent the pivot of the latter and eccentric with reference to said pivot. It is apparent, however, that the invention is not limited to providing this clamping surface on both members.

In connecting the loop 4 to the buckle, the anchoring members 6 are separated by 95 swinging them relatively about their common axis, thus permitting one of the inwardly turned portions 6^b to be inserted in the loop, after which the other portion 6^b of the other clamping member may be introduced in the opposite side of the loop. When tension is applied to the belt, the two anchoring members lie in the same plane and hold the two clamping surfaces in alignment 100 to swing them simultaneously about the axis 105 7, permitting the other end 4^a of the belt to be passed between said clamping surfaces and the rear face of the front plate 1.

What I claim as my invention and desire to secure by Letters Patent is:

1. A belt buckle comprising a frame having a clamping surface, a pivotally mounted 5 clamping means embodying two relatively movable members, each of which has a belt engaging portion extending toward the belt engaging portion of the other member, said members having relative movement to permit 10 separation of the belt engaging portions, and a clamping surface for cooperation with the clamping surface on the buckle frame provided on at least one of the belt anchoring members to swing toward and from the 15 clamping surface on the buckle frame as the two members are swung simultaneously on their pivot.
2. A buckle comprising a frame having a front plate and laterally projected side flanges, belt anchoring means supported from said side flanges to swing about a suitable axis, said belt anchoring means embodying two members each having a belt

engaging portion extending toward a belt engaging portion of the other member, said 25 members having relative movement to permit the separation of said belt engaging portions, and a belt engaging surface carried by said belt anchoring means and adapted to swing with the latter about the 30 axis to cooperate with the rear face of the front plate.

3. A buckle comprising a buckle frame having a clamping surface, a shaft supported by said buckle frame, two belt anchoring members mounted to turn relatively to each other on said shaft, and each having a belt engaging portion extending toward the belt engaging portion of the other member, and two clamping surfaces each arranged 40 on one of the belt anchoring members to swing with the latter about their axis toward and from the clamping surface on the buckle frame.

JOHN HEBERLING.
